WIRE TRANSFER APPARATUS

Application filed December 2, 1929. Serial No. 411,145.

The present invention relates to the handling of wire in coiled form for the manufacture of fences and the like, and has more particular reference to an improved device for use in transferring formed coils of wire from the forming block to the reel from which the wire is directly taken in the manufacture of wire fence fabrics.

At the present time, the manufactured wire is wound upon a form block or the like and after the coil is formed to the desired size it is then stripped from the block, placed upon a cruciform frame and bundled or tied thereto, and then put on a truck. The truck is then moved to a fence department and unloaded by placing the coiled wire on reels from which the wire is unwound in the manufacture of the fence fabrics.

In order that the coils of wire may be readily handled and transported by truck, it has been found necessary to make relatively small bundles or coils of wire which are about 300 pounds each in weight.

According to the present invention the coils of wire may be made considerably larger and may be approximately 1000 pounds in weight each, and wherein the mounting and tying of the coils of wire to a frame is eliminated, and also the use of the truck may be eliminated.

An object of the present invention is to provide a transfer device which may be used directly between a portable reel and the form block so that the coil of wire may be transferred directly from the form block onto the reel and then the reel shifted to the desired point for feeding the wire directly therefrom to the machines for making the wire fence fabrics.

Another object of the invention is to provide a transfer device which may be quickly and easily detached from the reel and from the form block, and which may be quickly and easily adjusted into place between the reel and the form block so that the time required for the transfer is reduced to a minimum and wherein the transfer device may be quickly and easily handled.

With the foregoing and other objects in view, the invention will be more fully described hereinafter, and will be more particu-

larly pointed out in the claims appended hereto.

In the drawings, wherein like symbols refer to like or corresponding parts throughout the several views

Figure 1 is a side elevation, partly in section, of the transfer device constructed according to the present invention and as applied to the wire reel and the form block.

Figure 2 is a detail side elevation of the transfer device.

Figure 3 is a front side elevation of the same, looking into the upper reduced end of the device.

Figure 4 is a rear side elevation of the same.

Figure 5 is a top plan view of the device.

Figure 6 is a transverse section taken through the base or larger end of the device substantially on the line 6-6 of Figure 2, and

Figure 7 is a transverse section through the upper end of the device taken substantially on the line 7-7 of Figure 2.

Referring to the drawings, 10 designates the longitudinal supporting rods of the frame block which are connected at one end to a head flange or disc 11 against which the coils of wire are adapted to be pressed during the winding or coiling, and 12 designates a connecting outer ring to which the opposite ends of the bars 10 are secured. The ring 12 is located at the inner sides of the bars 10 so that the coil of wire, indicated at 13, may be slid outwardly from the head 11 over the opposite ends of the bars 10.

As the wire is drawn or manufactured it is wound upon the form block thus described, and when the coil is completed it is adapted to be transferred by suitable means and in a suitable manner to the reel 14, shown in Figure 1. The reel 14 may be of any suitable construction and is shown in the present instance as comprising a main cylindrical body portion mounted upon a base plate 15 adapted for rotation upon a spindle or shaft 16 which rises through the reel 14 and extends slightly above the same. The shaft 16' is mounted upon a base 16 having castors or rollers 17 by means of which the reel may be quickly and easily transported over the floor

or the like from place to place. The reel 14 is supported at its lower end by the base 16 and at its upper end by a spider frame 18 which is arranged within the upper end of the reel 14 so as to leave the upper end of the reel free and unobstructed for the passage of the coil 13 thereover.

The transfer device of the present invention comprises a pair of rings 19 and 20 which are connected together by a plurality of wires or rods 21 secured at one end to the ring 19 and at their other ends to the ring 20. The ring 19 forms the base ring and adapted when in position to be disposed horizontally and is provided with a central hub 22 adapted to freely fit over the upper end of the shaft 15 and with arms 23 which extend radially from the hub 22 to support the ring 19. The ring 19 is connected to the outer ends of the arms 23 near the upper surface of the ring 19 so that the cavity or seat is formed in the lower side of the ring adapted to receive the upper end of the reel 14. The ring 19 is thus held upon the reel 14 so that the transfer device will not tilt when it rests upon the upper end of the reel, and the hub 22 of the transfer device engages the shaft 15 sufficiently to substantially center the base portion of the transfer device over the upper end of the reel.

The wires or rods 21 which form the body part of the transfer device are suitably curved so as to dispose the upper ring 20 at substantially right angles to the ring 19, or at such angle as is found convenient for the application of a transfer device between the form block 10 and the reel 14.

The lower or base ends of the rods 21 are suitably secured to the base ring 19 at the outer side thereof, or at any other suitable or convenient point, and the rods 21 converge upwardly and toward one side of the device as shown in Figure 1 and are secured to the inner side of the ring 20. The ring 20 is of less diameter than the ring 19 so that the upper end of the device tapers or is sufficiently reduced in diameter to freely receive the coil of wire 13 upon the device and to direct the coil of wire into position over the upper end of the reel 14.

The ring 20 has an exterior diameter to freely fit in the ring 12 of the form block, and any suitable means may be provided for limiting or suitably interconnecting the rings 12 and 20 so that the same are related as shown in Figure 1.

The transfer device may be retained permanently upon the upper end of the reel 14 so as to be transported therewith as a part thereof and so that it is only necessary to swing the ring 20 into alignment with the ring 12 of the forming block when it is desired to load the reel 14. In unloading the reel 14 the wire is merely unwound therefrom so that the transfer device plays no part in this op-

eration and is not in the way when carried upon the upper end of the reel.

It is apparent that in the use of the device all of these intermediate steps which are usually required for the transfer of the coil 13 from the form block 10 to the reel 14 is eliminated. It is only necessary to place the transfer device of this invention between the reel 14 and the form block 10 and to then slide the wire coil 13 from the form block over the transfer device to the reel 14.

The transfer device may be quickly detached from both the reel 14 and the form block 10 so that a single transfer device may be used continuously between a number of form blocks 10 and a number of reels 14. The operations of trucking, hoisting and independently conveying the wire coils 13 is thus eliminated, and the wire coils 13 may be made considerably larger than they are at present so that greater quantities of the material may be handled and the transfer is required at greater intervals of time.

The device is of such construction that it admits of solidity and strength while at the same time it is relatively small and light in weight and may be quickly and easily handled.

It is obvious that various changes and modifications may be made in the details of construction and design of the above specifically described embodiment of this invention without departing from the spirit thereof, such changes and modifications being restricted only by the scope of the following claims.

What is claimed is:—

1. In combination with an open ended form block for wire coils, a reel, means for supporting the reel for transportation from place to place, and an upwardly tapering and laterally curved transfer device having an opening in its lower end receiving the upper end of the reel and supporting the adjacent end of the device over the upper end of the reel, and having its upper end detachably engaging in the open end of the form block for receiving and guiding a coil of wire from the form block onto the reel.

2. A wire coil transfer device adapted for use between a form block and a reel, comprising a pair of rings of different diameters, and a plurality of rods secured to the inner wall of the ring of smaller diameter, and to the outer wall of the ring of larger diameter in spaced relation thereabout to provide a body portion, said rods being curved longitudinally to shape the body portion into the form of an elbow, the first mentioned ring having a smooth outer surface adapted to engage in the open end of the form block for receiving a wire coil therefrom and the second mentioned ring adapted to receive the end of the reel.

3. A wire coil transfer device adapted for use between a form block and a reel, com-

prising a main body part, means at one end of the main body part for detachable engagement with the form block and means at the opposite end of the main body part for detachably seating upon the reel, said last mentioned means comprising a ring carried by the main body part and a spider carried by the upper portion of the ring, forming a cavity in the lower portion of the ring to receive the upper portion of the reel.
